PRICE TAG HOLDER FOR COUNTERS

Robert J. Slavsky, Detroit, Mich., assignor to Shaw and Slavsky, Inc., Detroit, Mich., a corporation of Michigan

Application July 14, 1954, Serial No. 31,417

Term of patent 14 years

(Cl. D80—1)

I claim:

The ornamental design for a price tag holder for counters, as shown.
